UNITED STATES PATENT OFFICE.

JOHN J. SULLIVAN, OF IPSWICH, MASSACHUSETTS.

MACHINE FOR SEWING ON BUTTONS.

SPECIFICATION forming part of Letters Patent No. 600,297, dated March 8, 1898.

Application filed July 12, 1897. Serial No. 644,282. (No model.)

To all whom it may concern:

Be it known that I, JOHN J. SULLIVAN, a citizen of the United States, residing at Ipswich, in the county of Essex and State of Massachusetts, have invented certain new and useful Improvements in Button-Sewing Machines, of which the following is a specification, reference being had therein to the accompanying drawings.

10 My invention has for its object to provide an improved button-supplying device for button-sewing machines by means of which buttons of different sizes may be fed to the stitch-forming mechanism of a sewing-machine in such a manner that the button-chute will at all times be kept filled, so that the supply of buttons passing to the needle of the machine will never fail. With the form of button-hopper such as is shown in my Patent No. 595,742, dated December 21, 1897, and having a curved shank-receiving slot in its bottom opening out into the shank-slot in the chute a continuous supply of shoe-buttons will always be fed to the needle of the machine; but with buttons such as are used on gaiters or leggings and which have larger and flatter heads than shoe-buttons some difficulty has been experienced in keeping the button-chute filled. This difficulty has been obviated by the present invention, in which a slot is formed at one side of a fixed or stationary button-hopper between the vertical wall and the horizontal bottom of the latter, said slot having near one end an inclined shank-gate or exit-passage opening out into the shank-slot of the button-chute. Said inclined slot or passage forms what may be termed a "switch" to direct the buttons (the shanks of which are pressed by revolving brushes flatwise against the vertical wall of the button-hopper above said slot and through which latter the heads of the buttons project) into the button-chute. A stop-finger which projects slightly inward from the inner wall 45 of the hopper is preferably provided at the far side of the inclined shank exit passage or gate referred to to prevent the buttons pressed against by the revolving brushes from passing the said gate, said brushes serving to force 50 the buttons positively outward from the hopper into the button-chute.

In the accompanying drawings, Figure 1 is

a rear side elevation of a button-sewing machine with my invention applied thereto. Fig. 2 is a plan view of the hopper and top of the button-chute. Fig. 3 is a partial side elevation of the same. Fig. 4 is a partial vertical section of the same, and Fig. 5 a detail to show the button-exit from the hopper. Fig. 6 is a cross-section of the cylindrical upper part of the button-chute.

The button-sewing machine herein shown is essentially the same in construction and operation as that fully described in my Patent No. 596,020, dated December 21, 1897.

A denotes the button-hopper, fixedly mounted on the frame B of the machine. The vertical wall *a* of the hopper is cut away at its bottom on one side of the hopper to form the slot or opening *a'* between said wall and the horizontal bottom *a²* of the hopper, this slot or opening being of a proper size or width vertically to permit the heads of the reversed buttons *b* to project outward through said slot or opening, with their shanks disposed flatwise against the inside of the vertical wall of the hopper as the said buttons are pressed against by revolving brushes *d*, traveling around in the bottom of the hopper and carried by a vertical shaft *e*, provided at its lower end with a worm-wheel *e'*, meshing with a worm *e²* on the rotating driving-shaft E of the machine.

The button-chute comprises the cylindrical upper part F, having the spiral shank-slot *f*, the lower inclined part F' having the shank-slot *f'* and the curved plates *f²* separated from each other to form between them the shank-slot *f³*, communicating with the spiral slot *f*, which in turn communicates with or opens into the slot *f'*. The shank-guideway at the button-exit from the button-hopper to the slot *f³* is inclined, as is more clearly shown in Fig. 5, forming a switch which turns the button-shanks, which are forced against the inner wall of the hopper above the slot or opening *a'* by the brushes *d* outward into the slot *f³* at the top of the button-chute. This inclined shank-guideway or exit-passage is above the said slot or opening *a'* and extends horizontally outward through the bottom of the wall *a*, (see Fig. 4,) said inclined exit-passage being formed by the outwardly and inwardly bent fingers *a³* and *a⁴*, formed from

the metal of the wall of the hopper A, the finger a^4 on the far side of the inclined button-shank guideway or exit-passage f^4 preferably projecting inwardly slightly from the line of the inner side wall of the hopper to form a stop which prevents the button-shanks from passing the inclined guideway or exit-passage f^4 and thereby insures the exit of the buttons from the hopper and their entrance into the button chute or guideway under the action of the revolving brushes d , which, as stated, force the buttons outward positively from the hopper into the button-chute. Thus when the machine is in operation the button-chute is always kept filled, so that there will be an unfailing supply of buttons passing to the stitch-forming mechanism of the machine. I am aware that reciprocating or oscillating button-hoppers disposed in inclined positions and provided with slots through which the heads of the buttons might project outwardly through or beyond the side walls of the hoppers on their way to the button-chutes have heretofore been used, said hoppers having within them oscillating agitating brushes; but in the use of the devices referred to the buttons were not positively forced into the button-chutes by the brushes, but gravity was relied upon to carry the buttons agitated by the movements of the hoppers and brushes into the button-chutes. As a consequence the supply of buttons sometimes failed in the button-chutes, a difficulty which is altogether obviated by my invention.

Owing to the fact that the buttons enter the button-chute with their shanks upward, it is necessary to give them a partial turn, so that they may be presented to the needle with their shanks horizontal to permit the needle to pass through the eyes of the button-shanks, and this is effected by the spiral slot f , which gives the buttons a quarter-turn as their shanks pass downward in said slot.

The cylinder F has within it a central spindle f^6 , against which the heads of the buttons impinge and which thus serve to prevent the shanks of the buttons from escaping from the spiral slot f .

Having thus described my invention, I claim and desire to secure by Letters Patent—

1. In a button-sewing machine, a fixed button-hopper provided with a button-head-receiving slot between the bottom of a portion of the vertical wall of said hopper and the horizontal bottom thereof, and with an inclined button-shank exit-passage near one end of said slot, said exit-passage being above said slot and extending horizontally through said wall, combined with a button-chute having a button-shank slot into which the said

button-shank exit-passage opens, and means, as rotating brushes, within said hopper, for forcing the buttons outward from said hopper into said chute.

2. In a button-sewing machine, a fixed button-hopper provided with a button-head-receiving slot between the bottom of a portion of the vertical wall of said hopper and the horizontal bottom thereof, and with an inclined button-shank exit-passage near one end of said slot, said exit-passage being above said slot and extending horizontally through said wall, combined with a button-chute having a button-shank slot into which the said button-shank exit-passage opens, one side of said passage being formed by a finger projecting inwardly within the vertical line of the inner wall of the said hopper, and means, as rotating brushes, within said hopper, for forcing the buttons from said hopper into said chute.

3. The combination with the fixed hopper A having the slot or opening a' at its bottom, and the inclined button-shank exit-passage f^4 near one end of said slot or opening, of the button-chute consisting of the part F having the central spindle f^6 and the spiral button-shank slot f , the part F' having the button-shank slot f' , and the separated plates f^2 having the button-shank slot f^3 between them and into which slot f^3 the said inclined exit-passage f^4 opens.

4. The combination with the fixed hopper A having the slot or opening a' at its bottom, and the inclined button-shank exit-passage f^4 near one end of said slot or opening, of the button-chute consisting of the part F having the spiral button-shank slot f , the part F' having the button-shank slot f' , and the separated plates f^2 having the button-shank slot f^3 between them and into which slot f^3 the said inclined exit-passage f^4 opens.

5. The combination with the fixed hopper A having the slot or opening a' at its bottom, and the inclined button-shank exit-passage f^4 near one end of said slot or opening, of the button-chute consisting of the part F having the spiral button-shank slot f , the part F' having the button-shank slot f' , and the separated plates f^2 having the button-shank slot f^3 between them and into which slot f^3 the said inclined exit-passage f^4 opens, one side of said exit-passage being formed by the inwardly-projecting finger or stop a^4 .

In testimony whereof I affix my signature in presence of two witnesses.

JOHN J. SULLIVAN.
